UNITED STATES PATENT OFFICE

152,228

DESIGN FOR A LATHE

Clifford Brooks Stevens, Milwaukee, Wis., assignor to Rockwell Manufacturing Company, Pittsburgh, Pa., a corporation of Pennsylvania

Application December 19, 1947, Serial No. 143,236

Term of patent 14 years

(Cl. D54—6)

To all whom it may concern:

Be it known that I Clifford Brooks Stevens, a citizen of the United States, residing in Milwaukee, in the county of Milwaukee and State of Wisconsin, have invented a new, original, and ornamental Design for Lathe, of which the following is a specification, reference being had to the accompanying drawing, forming a part thereof.

Figure 1 is a front perspective view of a lathe, embodying my new design.

Figure 2 is a rear perspective view of the lathe of Figure 1.

Figure 3 is an end perspective view of the lathe of Figure 1 viewed from the head stock end, and

Figure 4 is an end perspective view of the lathe of Figure 1 viewed from the tail stock end.

I claim:

The ornamental design for a lathe, substantially as shown.

CLIFFORD B. STEVENS.
